UNITED STATES PATENT OFFICE.

CLARENCE W. BLACKSTONE, OF CHICAGO, ILLINOIS, ASSIGNOR, BY MESNE ASSIGNMENTS, TO BURT MACHINE COMPANY, OF BALTIMORE, MARYLAND, A CORPORATION OF DELAWARE.

CAN-LABELING MACHINE.

1,168,476.

Specification of Letters Patent.

Patented Jan. 18, 1916.

Application filed May 24, 1910, Serial No. 563,179. Renewed December 21, 1915. Serial No. 68,042.

To all whom it may concern:

Be it known that I, CLARENCE W. BLACKSTONE, citizen of the United States, residing at Chicago, in the county of Cook and State of Illinois, have invented certain new and useful Improvements in Can-Labeling Machines, of which the following is a specification, reference being had therein to the accompanying drawing.

10 The present invention relates to labeling machines of the character adapted to apply, and affix, to a can, box, or other package, a label, while the can or package is fed from the feed to the delivery end of the machine.

15 More particularly the invention has to deal with novel pasting instrumentalities, whereby the label, when affixed to the can or package will be practically devoid of the customary and objectionable wrinkles, and 20 will fit smoothly around the engaged can.

It has been customary in the labeling machine art to apply paste or cement by means of belts, brushes, etc., either directly to the can body or the body of the label to be

25 applied to said can body and in either event, when applied, substantially the entire surface of the label would be coated. This manner of application has many advantages but is objectionable to a large extent, pri-

30 marily because of the wrinkling of the applied label incident to the expansion thereof due to the dampening or moistening of the entire surface of the label. It has also been suggested to partly overcome this objection

35 by applying the paste to the opposite ends only of the label, but the upper and lower edges of the label would be free, and this has proven objectionable since it leaves the joint between the cap and body of the can

40 unsealed, and the contents of the can are not protected from outside influences.

It may be said to be the primary object of the present invention to overcome the existing objections to coating the entire surface

45 of the label, or substantially the entire surface thereof, and at the same time to form, by the label a practically air tight joint between the cap or top and the body of the can. With this end in view, the invention

50 includes means whereby a label is pasted at that edge or portion thereof which overlies the joint between the cap and body of the can as distinguished from coating the entire surface thereof.

55 More particularly the invention includes

a can feed mechanism, paste applying instrumentalities for placing upon a portion of the can a body of paste extending entirely around the circumference thereof, means for temporarily interrupting the travel of the can along the run way during the pasting operation, and novel releasing mechanism for said last mentioned means whereby the can feed will continue and a label will be picked up and applied and 65 affixed to the can.

One of the novel characteristics of the present construction resides in the means for positioning and holding a can in position relative to the paste applying instrumentalities, which, more particularly stated may be said to reside in a stop or pocket arranged in the path of a fed can and adapted to be engaged by the can to firmly support the same in operative position and interrupting 70 the travel thereof along the run way, while permitting the can to rotate relative to the paste applying mechanism, all of which will be more particularly referred to hereinafter.

Other improvements and novel details in 80 the construction and arrangement of parts will be brought out in the description following which, for a clear understanding of the invention should be read in connection with the accompanying drawings forming a 85 part hereof and which, for the purpose of illustration disclose a convenient and satisfactory embodiment of the invention.

In the drawings: Figure 1 is a view in front elevation of the machine. Fig. 2 is 90 a front end elevation. Fig. 3 is a vertical section along the line 3—3 of Fig. 1, and Fig. 4 is a detail view enlarged of the front of the machine toward the forward end, disclosing more particularly the can support 95 for holding the can in position to be pasted, together with releasing mechanism for said support. Fig. 5 is a detail view of the latch or lock for the can rest. Fig. 6 is a perspective view of the can holder.

Referring now more particularly to the drawings wherein like reference numerals refer to corresponding parts throughout the several views 1 is a base support of any suitable material and construction and having mounted thereon suitable frame work, conveniently metal, and adapted to support the operative parts of the machine. Longitudinally extending supports 2 resting upon bracket arms 3 and 3^a of the supporting 100

105

110

frame have at or adjacent their respective ends bearing members 4 in which are mounted journals 5 and 5^a for front and rear pulleys 6 and 6^a respectively. The said pulleys 5 and 6^a are conveniently grooved at their peripheries as clearly indicated in Figs. 2 and 3 and are adapted for the reception of belts 7, which conveniently take the form of a round cross section. The walls of the peripheral grooves of the pulleys 6 and 6^a are conveniently oppositely inclined whereby is provided a wedge engagement for the belts, thereby tending to prevent any slipping of the belts relative to the pulleys. The belts 7 may be termed the feeding mechanism for the cans, since the same are adapted to engage the peripheral surface of the cans preferably adjacent opposite ends thereof and impart forward turning movement to the cans along a run way positioned beneath the belts, the said run way to be presently described.

Positioned upon the journal 5, but outside of the respective pulleys 6 are relatively flat circular disk members 8 of a diameter slightly greater than the diameter of the pulleys for a purpose about to be described.

A longitudinally extending inclined run way 9 projects beneath and forwardly of the disk members 8, the run way, which may be termed a delivery run way being spaced from said disks a sufficient distance to permit a can to roll downwardly along the run way and beneath the disk 8.

35 The feed runway is indicated by the numeral 10 and at the forward end thereof projects downwardly a supporting bracket 11 which latter constitutes a bearing for a tread or trip member 12 having an angled downward extension 13 the tread member or trip being pivotally supported to said bracket by the pintle or journal 14. The normal position of the trip or tread member 12 places the forward end thereof adjacent to the lower end of the delivery runway 9 with the body of the trip slightly above the lower end of said runway and having its end curved at 15 so as to be engaged by the can as it leaves the runway 9.

50 Positioned below the runway 10 at a point adjacent the forward end thereof but spaced rearwardly of the trip member 15 is a paste receptacle 16 of any desired construction, the same being mounted on a suitable bracket or support 17 of any convenient construction, and arranged for rotary movement in said receptacle is a paste applying roller 18 of any desired material but preferably having a metallic body, the said roller being mounted on a shaft 19 which shaft is loosely journaled in the sides of the receptacle and one end of which projects beyond the receptacle and has mounted thereon a drive pulley 20 which through the medium of a belt 21 is driven by a pulley

22 mounted on the journal 5 of the pulleys 6. The said pulley 22 receives its power from any suitable drive not shown.

The paste applying roller 18 is in the form of a relatively narrow disk and may have the usual yielding surface and is so positioned in the receptacle that the periphery thereof will overlap the joint between the cap X' and body of the can X.

Suitable guide bars 23 one of which is yieldably supported through the medium of the pivoted connection 23^a and spring 23^b constitute means for engaging opposite ends of the can to hold the same in position whereby the joint between the cap and body of the can will overlie the periphery of the paste applying roller 18. Since the width of the can tops may vary the paste applying roller is conveniently adjustable upon the shaft 19, the same being held in adjusted positions by a suitable bolt or the like 24. In order that the opposite tracks of the run way 10 may afford a firm support for the can during its feed therealong, the tracks or rails of the run way are somewhat wide as clearly shown in the drawings, and that track adjacent to the paste receptacle is cut away immediately above the paste roller at 25 whereby the periphery of the roller may play through said cut away portion and constitute in effect a portion of the run way to contact directly with the joint between the cap and body of the can as clearly illustrated in Figs. 2 and 3.

55 Mounted to one side of the paste receptacle immediately below the path of the cans and upon the support 17 is a standard 26 having a transversely extending aperture 27 adapted for the reception of a shaft 28 the opposite ends of which shaft project beyond 105 opposite sides of the standard 26 and loosely fitted thereto for rocking movement are brackets 29, which said brackets are substantially triangular in shape as shown.

Projecting between the brackets transversely of the run way are rollers or idlers 30 the said rollers being connected at the opposite corners of the brackets 29 and form therebetween a pocket or seat for the reception of a can and properly positioning the 110 same relative to the pasting roll 18.

60 It will be seen that normally the rollers 30 occupy a position whereby the periphery thereof projects above the upper surface of the run way 10, and that portion of the 120 run way forwardly of the rollers 30 has an inclined upper surface 10^a so as to guide the can to the upper surface of the foremost roller, to the end that the foremost roller offers no obstruction to the feed of the can, which latter falls behind the foremost roller into contact with the run way 10, the other roller 30 constituting a stop or abutment for interrupting the feed of the can along the runway. As before described the brackets 125 65

or supports for the roller 30 are mounted for swinging or rocking movement, a spring 31 of any desired construction secured at one end to the shaft 28 at its opposite end to the adjacent bracket 29 tending to impart swinging movement to the bracket, and a stop for limiting said swinging movement is provided by a projection 32 on the bracket 29 adapted to engage a lug or projection 33 of any desired construction on the runway 10.

Means are provided for locking the bracket members 29 in elevated position, so as to prevent the can as it moves into contact with the rearmost roller from swinging the same against the action of the spring 31 downwardly, until a strip of paste has been applied to the can about its entire circumference. This means comprises a locking member or latch 34 adapted to engage a lug or projection 35 on one of the bracket members 29, said latch being slidably mounted in a guide way 36 secured to the track of the runway which supports the bottom or lower end of the can. The latch member 34 has a downward extending ear 37 which constitutes means for limiting the inward movement of the latch by contacting the end of the guide member 36, and also constitutes a bearing for a pintle or lug 38 secured to an elongated arm 39 extending longitudinally of the machine and having a sliding engagement with a suitable bracket support 40 projecting downwardly from the forward end of the runway.

Adjacent the end of the rod or arm 39 is a nut or collar 41 adjustably mounted in any desired manner and conveniently held in adjusted positions by a suitable bolt 42. Positioned between the nut or sleeve 41 and the support 40 and mounted upon said rod 39 is a suitable spring 43 in the form of a spiral the action of which spring is to impart forward movement to the latch member 34 into contact with the stop 35 of the bracket member 29. From the description of the structure just referred to, it will be seen that the can when positioned in the pocket or recess formed between the rollers 30 will be in contact with the pasting roller 18 and will be held in such contact until the locking member or latch 34 is released in a manner presently to be described, and the movement of the feed belts 7 will continue to impart rotary movement to the cans, the rollers 30 constituting antifriction bearings to permit of said rotary movement while preventing rolling movement of the cans along the runway.

While the pasting mechanism is in the form of a roller it is obvious that other paste applying mechanism may be employed, the essential feature being that the can is held in contact with the paste applying mechanism a sufficient interval to produce a pasted

surface of limited width entirely around the can.

The releasing mechanism for the latch 34 includes the trip member 12 previously described, the angled or downward extension 13 having on its surface a yieldable contact or buffer member 44 with which the forward terminal of the rod 39 contacts. When pressure is applied to the trip member 12 the same will swing about its pivotal connection 14 and the downward extension 13 will impart through the buffer 44 longitudinal movement of the rod 39 and in turn to the sliding latch 34 with the result that the only retaining means for holding the bracket elevated is the spring member 31 which will be overcome by the weight of the can under the action of the drive belts 7. So soon as the can is released from the pocket formed by the rollers 30 the same will continue in its rolling movement along the runway 10 and will contact with a suitable pasting roll or the equivalent thereof 45 of any desired construction and mounted for rotary movement in any desired manner in the paste receptacle 46. The purpose of this pasting roller is to place a dab of paste on the body of the can extending longitudinally thereof and adapted to engage with the forward end of a label positioned in a label receptacle 47 of any of the desired forms. In the continued movement of the roller along the runway the label is wound around or about the can, and the free or lap end of the label may receive a coating of paste as is customary in labeling machines of this character.

At the rear end of the machine is a yieldable support 48 immediately below the pulleys 6^a, the latter exerting pressure on the can, so as to affix the lap end of the label to the can in a manner well understood in the art.

The operation of the machine may be briefly reviewed as follows: Any of the approved styles of spacing mechanism for the cans may be employed, such for instance as illustrated in the co-pending application of Knapp and Blackstone Serial No. 479,292, the cans being fed from the spacing mechanism along the delivery runway 9 into contact with the pressure rollers or disks 8 and the forward end 15 of the trip member 12. The rotation of the disks 8 imparts forward movement to the cans and at the same time presses the trip member downwardly about its pivotal connection 14, the trip member 15 being held elevated by the rod 39 through the medium of the spring 43, and when so elevated it will be appreciated that the space between the rollers or disks 8 and the trip member 12 is less than the length of the diameter of the cans with the result that the trip will be lowered as stated and the can moved by the disk 8 along 130

the runway 10 into contact with the feed belts 7 which latter continue the feed movement of the can along the inclined surface 10° of the runway and over the foremost 5 roller 30 when the can will contact with the rearmost roller 30 and rest in a pocket formed by the rollers 30 and held in said pocket as previously described for the pasting operation. Rotary movement being imparted to both the seated can and the pasting roll, a thin coating of paste is applied entirely around the can at the junction of the flange of the lid with the body, and when so coated the pasted can is released by 10 the next succeeding can engaging the trip member 12 whereby the latch 34 is released and the bracket 29 swung about its pivot against the action of the spring 31 by the foremost can until the stop or rearmost 15 roller 30 assumes a position below the runway 10 when the foremost can continues its rolling movement imparted by the feed belts 20 7. As soon as said foremost can passes beyond the stop or rearmost roller 30 said 25 roller will be lifted into position to contact with or stop a succeeding can, through the medium of the spring 31, and the latch 34 thereupon moved into engagement with the stop 35 by the action of the spring 43 which 30 at the same time moves the trip member 12 into position to be engaged by a succeeding can. The pasted can in its continued movement receives a daub of paste which engages the foremost end of a suitably supported 35 label, which label is wound about the can, and the lap ends affixed in any desired manner. By reason of the fact that the runways are of a width greater than the depth of the top X' of the can, it will be appreciated that 40 the belts 7 will exert sufficient pressure to the cans as to firmly affix the label and cause the same to adhere to said pasted surface of the can at the junction of the top and body of the can, with the result that a practically 45 air tight joint is formed between said top and body.

Suitable guide pulleys 49 mounted in bearings in bracket members 50 secured to the longitudinally extending supports 2 may 50 be provided for engaging the belts 7 intermediate their ends and holding the same in a position whereby they will at all times engage the periphery of the cans and exert pressure thereto during the rolling action 55 of the latter, with the result that the label will be firmly affixed at the joint between the top and body of the can.

A suitably supported belt tightener 51 of any desired construction may also be provided for taking up any play in the endless belt or drive connection 21.

What I claim is:

1. In a labeling machine, the combination of a guide or runway for a can or the like, 60 means for feeding a can along the same,

paste applying instrumentalities arranged between the runway parts and offering substantially no obstruction thereabove adapted to produce a pasted surface of limited width entirely around the can at the junction of the flange of the lid with the body, and means adjacent the runway for interrupting the feed of the can along said runway while acted upon by said instrumentalities. 70

2. In a labeling machine, the combination 75 of a rotary paste disk of a width less than that of a can to be labeled, an antifriction support for a can or the like adjacent the feed, and means whereby the can is rotated to complete a revolution on said support 80 while in contact with said paste feed.

3. In a labeling machine, the combination 85 of pasting and labeling instrumentalities, means for feeding a can or the like relative to said instrumentalities, opposed rollers separated from one another and extending transversely of the runway for supporting and interrupting the feeding movement of the can when adjacent said pasting instrumentalities, said feeding means causing the 90 can to rotate in contact with the paste applying instrumentalities.

4. In a labeling machine, the combination 95 of a paste carrier, feeding mechanism for a can or the like, a support for a can or the like mounted adjacent to the paste carrier, said support being independent of the paste carrier and including antifriction bearings permitting the can to rotate over the paste carrier. 100

5. In a labeling machine, a runway, a support intermediate the ends of the runway for a can or the like, comprising oppositely disposed rollers extending transversely across the runway and adjacent thereto adapted to form therebetween a seat or pocket for a can or the like, a rocking support for said rollers and means for applying paste to the can while positioned in said seat. 105

6. In a labeling machine, a runway for 110 a can or the like, a can feed, a support intermediate the ends of the runway for a can comprising oppositely disposed antifriction devices adapted to form therebetween a seat or pocket for a can or the like, a common 115 supporting means for said rollers, said means being movable to release the can, and means for applying paste to the can while positioned in said seat.

7. In a labeling machine, a runway, a can feed, a support for a can or the like comprising elongated oppositely disposed members extending transversely of the runway and spaced from one another whereby to form therebetween a seat or pocket for a 120 can or the like, a swinging support for said members and means for applying paste to the can while positioned in said seat, said means permitting the can to rotate in said pocket. 125

8. In a labeling machine, the combination of a runway for a can or the like having disposed transversely thereof separated elongated members forming therebetween a pocket intermediate the ends of the runway adapted to receive a can and interrupt its feed along its runway, a rotatable disk for applying paste to the can adjacent the head only thereof while positioned in said pocket, labeling instrumentalities, and means for feeding the can from the pocket to said labeling instrumentalities.

9. In a labeling machine, the combination of a runway for a can or the like having transversely extending separated rollers forming a receiving pocket intermediate its ends, said pockets having anti-friction rollers adapted to engage a can and interrupt its feed along its runway, means for applying paste to the can while positioned in said pocket, labeling instrumentalities, means for releasing the can from said pocket, said means including a rocking support for said rollers, and means for feeding the can from the pocket to said labeling instrumentalities.

10. In a labeling machine, the combination of a feeding mechanism for a can or the like, pasting and labeling appliances over which the cans are adapted to pass, means adjacent the pasting appliances for constituting a receiving pocket and for interrupting the feed of the can at this point, said means being movable into and out of the path of the can, and means for rotating the can while in said pocket in contact with the pasting appliances.

11. In a labeling machine, the combination of a runway, labeling and pasting appliances, means for feeding a can along the runway, and a stop arranged in the path of the can to interrupt the feed thereof adjacent the pasting appliances, said feeding means being adapted to rotate the can in contact with the pasting mechanism for a complete revolution.

12. In a labeling machine, the combination of a runway, labeling and pasting appliances, means for feeding a can along the runway, and a stop arranged in the path of the can to interrupt the feed thereof adjacent the pasting appliances, said stop being movable into and out of the path of the can, and said movement being controlled by a succeeding can.

13. In a labeling machine, the combination of a runway, labeling and pasting appliances, means for feeding a can along the runway, and a stop arranged in the path of the can to interrupt the feed thereof adjacent the pasting appliances, said stop being movable into and out of the path of the can and constituting a rest or support permitting the can to rotate into contact with the pasting appliances, said feeding means constituting means for rotating the can

in said pocket in contact with the pasting appliances.

14. In a labeling machine, the combination of a runway, labeling and pasting appliances, means for feeding a can or the like along the runway, a stop adjacent the pasting appliances normally in the path of the can, and constituting a rest or support for holding a can from movement along the runway while in contact with the pasting appliances, and means for releasing said stop.

15. In a labeling machine, the combination of a runway, labeling and pasting appliances, means for feeding a can or the like along the runway, a stop adjacent the pasting appliances normally in the path of the can, and means whereby said stop is moved out of the path of the can by a succeeding can.

16. In a labeling machine, the combination of a runway, labeling and pasting appliances, means for feeding a can or the like along the runway, a stop adjacent the pasting appliances normally in the path of the can, and means for moving said stop out of the path of the can including a trip arranged along the runway and adapted to be actuated by a succeeding can.

17. In a labeling machine, the combination of a runway, labeling and pasting appliances, means for feeding a can along the runway and a releasable stop arranged in the path of the can adjacent the pasting appliances, and spring means for normally holding the stop, substantially as and for the purpose described.

18. In a labeling machine, the combination of a runway, labeling and pasting appliances, means for feeding a can along the runway, a spring pressed stop arranged in the path of the can adjacent the pasting appliances, and means for releasing said stop, substantially as and for the purpose described.

19. In a labeling machine, the combination of a runway, labeling and pasting appliances, means for feeding a can along the runway, a spring pressed stop arranged in the path of the can adjacent the pasting appliances, and means for releasing said stop, said means being actuated by a succeeding can, substantially as and for the purpose described.

20. In a labeling machine, the combination of labeling and pasting mechanisms, a runway for guiding a can or the like to said mechanisms, means for feeding the can along said runway, a stop arranged in the path of the can adjacent said pasting mechanism for interrupting said feed, and means actuated by a succeeding can for releasing said stop.

21. In a labeling machine, the combination of labeling and pasting mechanisms, a

runway for guiding a can or the like to said mechanisms, means for feeding the can along said runway, a stop arranged in the path of the can for interrupting said feed at a point adjacent the pasting mechanism, means actuated by a succeeding can for releasing said stop whereby the feed of the can may be continued, and spring means for holding the last mentioned means and the stop in operative positions.

22. In a labeling machine, the combination of labeling and pasting mechanisms, a runway for guiding a can or the like to said mechanisms, means for feeding the can along said runway, a stop arranged in the path of the can for interrupting said feed at a point adjacent the pasting mechanism, means actuated by a succeeding can for releasing said stop whereby the feed of the can may be continued, and a single spring means for holding said last mentioned means and the stop in operative positions.

23. In a labeling machine, the combination of pasting and labeling instrumentalities, a runway for a can or the like to said mechanisms, means for feeding the can along said runway, a stop arranged in the path of the can for interrupting said feed at a point adjacent the pasting mechanism, means actuated by a succeeding can for releasing said stop whereby the feed of the can may be continued, and spring means for holding the last mentioned means and the stop in operative positions.

ties, a runway for a can or the like, a stop arranged in the path of the can, adjacent said pasting instrumentalities, and a trip mechanism for said stop including oppositely disposed members between which a succeeding can passes, one of said members being yieldable.

24. In a labeling machine, the combination of pasting and labeling instrumentalities, a runway for a can or the like, a stop arranged in the path of the can adjacent said pasting instrumentalities, and trip mechanism for said stop including a yieldable member and a relatively fixed rotary member, said members adapted to be engaged by a succeeding can as it passes between said members.

In testimony whereof I affix my signature in presence of two witnesses.

CLARENCE W. BLACKSTONE.
